UNITED STATES PATENT OFFICE.

WILLIAM ALLEN, OF ROCKFORD, ILLINOIS, ASSIGNOR OF ONE-HALF TO
ANDREW M. JOHNSTON, OF SAME PLACE.

STARCH-WASHING MACHINE.

SPECIFICATION forming part of Letters Patent No. 275,819, dated April 3, 1883.

Application filed July 27, 1882. (No model.)

To all whom it may concern:

Be it known that I, WILLIAM ALLEN, a citizen of the United States, residing in the city of Rockford, in the county of Winnebago and State of Illinois, have invented a new and useful Starch-Washing Machine, of which the following is a specification.

This invention relates to the manufacture of starch, glucose, or grape-sugar, and its object is to wash the ground or reduced material containing the starch in such a manner as to separate the starch from the bran-shucks or other refuse matter and hold it in a free water solution. To this end I have designed and constructed the washing-machine represented in the accompanying drawings, in which—

Figure 1 is a plan view of a washing-machine embodying my invention, of which Fig. 2 is a side elevation. Fig. 3 is an end elevation. Fig. 4 is a transverse vertical section on dotted line *x*. Fig. 5 is a lengthwise vertical central section on dotted line *y* of a portion of the machine, and Fig. 6 is an isometrical representation of a rotary fan-like agitator.

As represented in the drawings, my improved washing-machine is cylindrical in outline form, and is composed mainly of like cylindrical sections *A*, preferably produced in castings in hollow cylindrical sections, and except the one end section, *B*, are each provided with a head, *C*, in one end, which heads, on their outer portions, are provided with a series of openings or perforations of any suitable or convenient form, substantially as represented in head *C* in Fig. 4. The inner surfaces of these cylindrical sections are at proper intervals provided with inward-projecting radial ribs *a*, extending lengthwise of the sections. The ends of these several sections are provided

with outward-projecting annular flanges *b*, which are provided at proper intervals with sufficient screw-bolts, by means of which, in connection with suitable packing placed between, the flanges are secured to each other, producing close joints. This cylinder produced from these sections is provided with heads *D*, of suitable dimensions to engage the ends of the cylinder, and are connected or joined to its ends in the same manner that the several sections are joined to each other by means of the usual screw-bolts and joint-pack-

ing. The heads of this cylinder are provided with flanged feet *E*, on which it is supported, and by means of which it may be fixed in position to the floor or supporting-frame by means of suitable screw-bolts.

At *c* are represented suitable stuffing-boxes, of the usual construction, formed upon the outside and axial center of the heads *D*. These stuffing-boxes are designed to receive an axial shaft supported in the axial center of the cylinder.

At *F* are represented arching supports fixed to the heads *D* and projecting outward therefrom. These supports are fitted with journal-bearings *d* to receive the journals of an axial shaft to revolve therein.

At *H* is represented a shaft of suitable dimensions and conformation, having its end portions produced in journal form. This shaft is placed in the axial center of the cylinder, having its journal-formed end portions passed through the stuffing-boxes, and supported to revolve in the bearings *d*, formed in the arching supports.

At *e* are represented spider-formed hubs fitted to receive the axial shaft *H* within the cylinder. One of these hubs is placed upon the shaft *H* in each section of the cylinder, and is securely fixed in position thereon. These several spider-formed hubs are provided with tangent arms *h*, projecting therefrom at equal quarter divisions. The faces of these tangent arms are slightly inclined to the axis of the shaft.

At *k* are represented fan-like agitating-blades slightly curved, having their inner ends securely fixed to the inclined face of the tangent arms *h*, which connection places the forward convex face of the blades oblique to the axis of the shaft.

At *K* is represented a suitable belt-pulley, which is mounted upon the end portion of the shaft *H*. This pulley is designed to receive a suitable belt employed to connect it with a prime mover in a manner to impart a rotary movement of the shaft, causing it to revolve to impart a rotary movement to the fan-blade in the direction indicated by the arrows.

At *N* is represented an induction-pipe, through which the material containing the starch is admitted into the cylinder to be

washed. In this instance the induction-pipe is placed near the bottom of the cylinder; but, if preferred, it may be placed in the position represented by the dotted lines, or in any other 5 position, preferably, however, in the end or bead of the cylinder.

At P is represented an outlet discharge-pipe placed in the end of the cylinder, near the bottom thereof. Through this pipe the 10 contents of the cylinder are discharged, to be conveyed to the starch-separating sieves.

In the use of my improved washing-machine the agitating fan-like blades are made to revolve at quite a high velocity. The ground or 15 otherwise reduced starch-containing material to be washed, being well saturated with water, is introduced to the machine through the induction-pipe N in contact with the rotating agitating fan-like blades, the action of which 20 will by means of centrifugal force throw it against the longitudinal radial ribs of the cylinder. This action, with other agitation of the contents of the cylinder, produced by the rotary agitator, will cause a separation of the 25 starch from the bran-shucks or other refuse material, producing a starch-water solution, and by reason of the oblique position of the agitating rotary fan-like blades relatively with the axis of the cylinder the material will be 30 forced lengthwise in the cylinder through the openings in the inner heads or transverse division-walls into the adjoining chamber, to be operated upon by another set of rotating agitating fan-like blades in like manner, which 35 30 action will be repeated in its passage through each section of the cylinder, and the contents of the cylinder, having passed through its several chambers and being thoroughly washed, will be discharged through the outlet-pipe P, 40 to be conducted to the separating-sieves.

In this instance I have represented my improved washer as constructed of a certain number of sections; but these may be varied by increasing or lessening their number to 45 adapt the machine to the requirements of the party using it. Instead of the machine being placed in a horizontal position, it may be inclined, being lowest at its discharge end, which will facilitate the discharge of its contents; 50 or it may be inclined in the opposite direction, which will operate to retard the discharge and insure a more thorough washing.

My improved washer is also capable of use placed on end, and by a suitable inclination

of the fan-like blades, when employed in this 55 position, the material to be washed may be fed to the cylinder, either at the lower or upper end, and discharged at its opposite end.

In the use of my improved machine the washing may be made more thorough by a continued additional supply of water introduced 60 into the cylinder during the process of washing.

I claim as my invention—

1. In a starch-washing machine, the combination, with a cylinder having radial lengthwise ribs projecting from its inner concave surface, and provided with an inlet and an outlet orifice or pipe, of an agitator rotating within the cylinder, said agitator having its fan-like blades oblique to its axis of rotation, substantially as and for the purpose set forth. 65 70

2. In a starch-washing machine, a cylinder composed of separate sections forming compartments, the heads of which form transverse division-walls, and which heads are provided 75 with a series of suitable openings or perforations, substantially as and for the purpose set forth.

3. In a starch-washing machine, a cylinder consisting of sections and end heads, each 80 section, except one of the end sections, provided with a head, said heads provided with suitable openings or perforations, the several sections and the end heads suitably joined to each other, producing a cylinder with closed 85 ends divided into separate compartments, substantially as and for the purpose set forth. 85

4. In a starch-washing machine, a cylinder composed of separate sections forming compartments, the heads of which form transverse 90 division-walls, which heads are provided with suitable openings or perforations, in combination with the agitators mounted to revolve within said compartments, substantially as and for the purpose set forth. 95

5. A starch-washing machine substantially as herein described, consisting of a compartment-cylinder composed of separate sections, the heads of which form transverse division-walls, the rotating agitators adapted to revolve within said compartments, the induction-pipe, and the outlet-pipe, substantially as and for the purpose set forth. 100

WILLIAM ALLEN.
